(57) **CLAIM**

The ornamental design for a set of pads for a restraint belt, as shown and described.

DESCRIPTION

FIG. 1 is a perspective view of a set of pads for a restraint belt showing my new design;

FIG. 2 is an end view of one pad of the set, the opposite end view having the same appearance;

FIG. 3 is a front view of one pad of the set, the rear of the pad having the same appearance; and,

FIG. 4 is a side view of one pad of the set, the opposite side of the pad having the same appearance.

Only one pad of the set is shown in FIGS. 2, 3 and 4 for ease of illustration. Both pads are identical in appearance. The broken lines showing a restraint belt are for illustrative purposes only and do not form part of the claimed design.
